COMBINED CARRYING AND DISPLAY CASE FOR COSMETICS OR THE LIKE

John V. Shinn, 2925 NW. Mulkey Ave.,
Corvallis, Oreg. 97330

Filed Aug. 10, 1972, Ser. No. 279,706

Term of patent 14 years

Int. Cl. D3—02

U.S. Cl. D87—1 R

FIG. 1

FIG. 3

FIG. 1 is an interior perspective view of a combined carrying and display case for cosmetics or the like showing my new design in open position;

FIG. 2 is a rear elevational view thereof on a reduced scale; and

FIG. 3 is a bottom plan view thereof.

I claim:

The ornamental design for a combined carrying and display case for cosmetics or the like, as shown.
